CLAIM

The ornamental design for an indirect luminous under cabinet light, as shown and described.

DESCRIPTION

FIG. 1 is an exploded perspective view of an indirect luminous under cabinet light in accordance with my invention.

FIG. 2 is a front elevational view of the indirect luminous under cabinet light of FIG. 1.

FIG. 3 is a back elevational view thereof.

FIG. 4 is a left elevational view thereof.

FIG. 5 is a right elevational view thereof.

FIG. 6 is a top plan view thereof.

FIG. 7 is a bottom plan view thereof.

FIG. 8 is a cross-sectional plan view taken in a direction of the line VIII-VIII shown in FIG. 3; and,

FIG. 9 is a cross-sectional partial perspective view taken in a direction of the line IX-IX shown in FIG. 1.

The evenly-spaced broken lines in the drawings depict portions of the indirect luminous under cabinet light that form no part of the claimed design. In FIGS. 1 and 3, the dash-dot-dash broken lines depict sectional designations that form no part thereof.

The indirect luminous under cabinet light is shown with a symbolic break in its length. The appearance of any portion of the indirect luminous under cabinet light between the dash-dot-dash lines forms no part of the claimed design.
